[57] CLAIM

The ornamental design for a fast service restaurant building, as shown and described.

DESCRIPTION

FIG. 1 is an upper front corner perspective view of a fast service restaurant building;

FIG. 2 is a top plan view thereof;

FIG. 3 is a front elevational view thereof;

FIG. 4 is a left side elevational view thereof, the right side being a mirror image of the left side;

FIG. 5 is a lower front corner perspective view of a modified embodiment of a fast service restaurant building of the design invention;

FIG. 6 is a front elevational view of the modification of FIG. 5;

FIG. 7 is a top plan view of the modification of FIG. 5;

FIG. 8 is a left side elevational view of the modification of FIG. 5; and

FIG. 9 is a right side elevational view of the modification shown in FIG. 5.

The broken line showing of indicia is for purposes of illustration only and to show the environment of the invention.

FIG. 1

FIG. 2

FIG. 3

FIG. 4

FIG. 5

FIG. 6

FIG. 7

FIG. 8

FIG. 9
